CLAIM

The ornamental design for divider wall coupling assembly, as shown and described.

DESCRIPTION

FIG. 1 is a front perspective view of the divider wall coupling assembly, as shown in conjunction with an enclosure and a divider wall;

FIG. 2 is a front perspective view thereof, shown in an open position of use;

FIG. 3 is a front perspective view of FIG. 2;

FIG. 4 is a rear perspective view of FIG. 2, as shown in conjunction with part of the divider wall;

FIG. 5 is a front view of FIG. 2;

FIG. 6 is a rear view of FIG. 2;

FIG. 7 is a first side view of FIG. 2;

FIG. 8 is a second side view of FIG. 2;

FIG. 9 is a top view of shown in a closed position of use;

FIG. 10 is a bottom view thereof; and,

FIG. 11 is a front perspective view of a divider wall coupling assembly of FIG. 1.

In the drawings, the broken lines depict environmental subject matter only and form no part of the claimed design.
